PRINTING MACHINE

Robert L. Hatfield, Cleveland Heights, Ohio, assignor to Addressograph-Multigraph Corporation, Wilmington, Del., a corporation of Delaware

Application January 16, 1942, Serial No. 426,973

4 Claims. (Cl. 101—47)

This invention relates to printing machines of the kind through which printing devices are sequentially fed.

In machines of the aforesaid character means, commonly known as a selector, are frequently provided and such means are operative to determine whether or not impression or other operations are to be formed on or from each printing device as it passes through the machine. One common use to which such a selector is put is to control operations of the impression making means, commonly known as the platen, that is operative to make impressions from each printing device as it reaches printing position in the machine.

A selector of the aforesaid character usually comprises detecting means adapted for cooperation with predetermined tabs, notches, openings or other indicia or lacuna provided on the printing devices at selected positions to be representative of a particular class or classes in a system of classification, and the selector also includes means responsive to the detecting means thereof which, in the instance of control of a platen, determine whether or not the platen will function to make an impression from the printing device when it attains printing position.

Machines of the aforesaid character are usually arranged to pass the printing devices through the machine in a step-by-step manner and operations are usually performed on or from the printing devices during the at rest periods in the course of the step-by-step movement thereof. Moreover, such machines are usually arranged for cyclic operation and the printing devices advance one step in each step-by-step movement thereof that is usually effected in the course of each cycle of operation of the machine. Furthermore, the machines are so arranged that each cycle of operation usually requires a predetermined period of time and heretofore where a selector mechanism has functioned in such a manner, for example, as to render the platen inoperative with respect to a particular printing device when it reaches printing position, so that an impression will not be made by the platen from such printing device whereby such device, at it is termed in the art, is skipped, just as much time is devoted to the cycle of operation in which such a printing device is skipped as when an impression or other operation is made on or from the printing device.

I have observed instances where, when a series of printing devices is passing through a printing machine, only a few of the printing devices in the series are so classified that the selector functions

to cause an operation to be performed thereon or therefrom. Yet in such an instance just as much time is required to pass the printing devices through the machine as would be required if operations were performed on or from each printing device.

In view of the foregoing it is the primary object of my invention to so pass printing devices through a printing machine or the like that those printing devices which are to be skipped, that is, which are not to have an operation performed thereon or therefrom, will pass through the machine much more quickly than will those printing devices that are to have an operation performed thereon or therefrom, and an object ancillary to the foregoing is to speed up the operation of the machine, or of selected parts thereof, when a printing device is to be skipped as aforesaid, and thereby pass such a device through the machine much more quickly than a device which is selected to have an operation performed thereon or therefrom.

With respect to the present invention it is to be understood that the term "printing device" is used herein in a generic sense with respect to printing devices of the kind disclosed, for example, in Gollwitzer Patent No. 2,038,865 or printing and control devices of the kind disclosed, for example, in Gollwitzer Patent No. 2,132,412. Moreover, the term "printing devices" is used herein generically with respect to devices which include a so-called frame on which a printing plate bearing embossed type characters is releasably retained and also so-called one-piece printing devices bearing embossed type characters and likewise stencil printing devices are intended to be included within the purview of the term "printing device" as are other and related devices.

The selectors that are included in printing machines and the like of the kind to which this invention relates sometimes include detecting means that cooperate with the printing devices, or identifying means thereon as tabs, lacuna or the like, immediately prior to the passage of these devices into the position in the machine whereat operations are performed thereon or therefrom. Furthermore, such selectors also sometimes include detecting means which cooperate with the printing devices, or identifying means thereon, in such a way that one or more cycles of operation of the machine intervene the time at which the detecting means of the selector cooperates with a particular device and the time at which the particular device reaches the position in the machine whereat an operation is to be performed thereon.

or therefrom. In this regard, however, it is another object of the present invention to enable those printing devices which are to be skipped to be quickly passed through the machine irrespective of the time at which the detecting means co-operate with each particular printing device, or identifying means thereon, to determine whether or not the device is to be skipped.

Other and more specific objects are to enable certain parts of a printing machine of the aforesaid character to be selectively operated at either a normal or a relatively high rate of speed; to so arrange the machine that it will normally operate at what may well be called a normal rate of speed, and also so that the machine or at least selected parts thereof, may be operated at a higher rate of speed when and as desired; to interpose an arrangement in the path of power transmission in a printing machine that power may be transmitted from one part to another selectively at a normal or at a relatively higher rate of speed; and to control the speed of such power transmission automatically in accordance with identifying means on the printing devices.

Other and further objects of the present invention will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a transverse sectional view of a printing machine embodying my invention and which is taken substantially on the line 1—1 of Fig. 2;

Fig. 2 is another sectional view of the machine substantially on the line 2—2 on Fig. 1;

Fig. 3 is a plan detail view of a part of the driving mechanism of the machine shown in Figs. 1 and 2;

Fig. 4 is a vertical sectional detail view taken substantially on the line 4—4 on Fig. 3;

Fig. 5 is a transverse sectional detail view taken substantially on the line 5—5 on Fig. 4;

Fig. 6 is a sectional view taken substantially on the line 6—6 on Fig. 5;

Fig. 7 is a fragmental vertical sectional view, taken along the line 7—7 of Fig. 8, and illustrating the embodiment of the invention in a printing machine of a different construction;

Fig. 8 is a fragmental rear elevational view, taken partially in section and illustrating the machine shown in Fig. 7; and

Fig. 9 is a fragmental vertical sectional view taken along the line 9—9 of Fig. 7.

The printing machines shown in the accompanying drawings are of the character through which printing devices are advanced one by one to an operative position in the machine whereat printing operations are performed. The machine shown in Figs. 1 to 6 of the drawings is generally of desk-like form and has an upstanding frame 100 providing a table top T upon which envelopes, letter, forms, or the like, may be positioned to receive printing impressions from the printing devices advanced to the aforesaid position in the machine. The frame 100 is so constructed and arranged that an operator may be seated in front of the frame, that is to the right

of the machine as shown in Fig. 1 of the drawings, so as to be adjacent to the front edge 101 of the table top T, and while seated in this working position the operator may place a sheet or the like over a printing position V (the aforesaid operative position, in the illustrated machine) which is provided beneath the table top T adjacent to the forward edge 101 thereof.

The printing devices D, as explained above, may be of any suitable character and are connected in the drawer K, Figs. 1 and 2, after passage through the machine, the drawer K being removably mounted in the machine. The printing devices D are initially stacked in a magazine M, Fig. 4, located on the table top T and these devices are withdrawn one by one from the bottom of the magazine and are advanced along a printing device guideway seriatim and in a step-by-step manner by suitable feeding means to the printing position V, and thereafter these devices pass to the drawer K wherein the printing devices are collected in the same sequence as that in which they were arranged when introduced into the magazine M. When a printing device D comes to rest at printing position V, a suitable printing or impression means, such as a platen mechanism P, may be operated to produce the desired printing impression from the printing device at this position onto the sheet or the like on the table top T.

In the use of printing machines of this general character it is customary to pass all of the printing devices in a particular group thereof through the machine even though printing impressions are not to be made from some of the devices. The devices that are so passed through the machine bear means by which they are classified, as for example, removable index tabs as disclosed in, for example, Gollwitzer Patent No. 2,049,436. Suitable means in the machine cooperate with means, as the index tabs, and so control operation of the machine that only those devices classified in a predetermined way are selected to have impressions made therefrom. Such selection may be performed visually by the operator in accordance with known practice and the operator may, through proper manipulation of the controls of the machine, cause the machine either to print from the printing devices or to skip such devices, as desired. In many instances, however, such selection is accomplished automatically under the governing action of the classifying or identifying means, as the aforesaid index tabs, provided on the printing devices. In the illustrated machine, such automatic selection is accomplished under the control of identifying means in the form of tabs 105 which are selectively mounted in any of a plurality of different identifying positions along the upper edges of the printing devices D. Therefore, when printing devices as D pass through the printing machine herein disclosed the means that cooperate with the tabs automatically function to effect a print or skip operation of the printing means in the machine in accordance with the presence or absence of tabs 105 at one or more selected positions on the printing devices. In such instances, it will be evident that there may be skip operations in a large proportion of the operating cycles of the machine.

In this regard it should be noted that in machines of the aforesaid character, the speed of operation is determined largely by the speed at which the machine may be operated when it is performing a printing operation. In prior machines the construction and arrangement has

been such that in skip operations just as much time was required as when a printing operation was being performed. In accordance with the present invention printing machines of the aforesaid character are arranged so as to reduce the operating time of the machine in skip operation, thereby to materially reduce the time required to pass a group of printing devices through the machine in those instances where many of the printing devices in the group are skipped.

In accomplishing this purpose the present invention provides for driving selected mechanisms of the printing machine at one speed when a printing operation is to be performed and for driving these mechanisms at a different and higher speed when a particular printing device is to be skipped. In attaining such increase of speed of operation during skip cycles of the machine, the present invention provides for automatic control of the speed of operation of the machine in accordance with the identifying means which control the print or skip operations of the machine.

The desired print or skip operation of the printing machine may be attained manually through selective manipulation of a plurality of foot pedal control devices 110, 111 and 112, Figs. 1 and 2, the foot pedal 110 constituting what may be termed the skip pedal of the machine, the foot pedal 111 constituting what may be termed the repeat pedal of the machine, and the foot pedal 112 constituting the consecutive foot pedal of the machine. It should be observed, however, that the control of the machine operation which is afforded through selective manipulation of the several foot pedals may in some instances be automatically modified by the selector means of the machine.

When the skip pedal 110 of the machine is momentarily depressed, it acts through a connecting rod 115 to actuate the clutch control lever 116 of a one revolution clutch 117, hereinafter termed the feed clutch of the machine, and this feed clutch cycle of operation serves to operate the printing device feeding means to advance the printing devices in the printing device guideway from one station to another along said guideway. When the repeat pedal 111 is momentarily depressed it acts through a connecting link 118 to operate a clutch control lever 119 of a one revolution clutch 120, hereinafter termed the platen clutch of the machine, and this platen clutch serves in each cycle of its operation to actuate the platen mechanism P through an operative printing cycle. When the consecutive foot pedal 112 is momentarily depressed it operates through a connecting linkage 121 to actuate the connecting links 115 and 118 of the feed clutch and the platen clutch so that the machine operates to perform a feeding operation upon the printing devices in the printing device guideway and to perform a printing operation from one of the printing devices at the time when such printing device is stationary at printing position P. Thus when the consecutive pedal 112 is employed to initiate successive cycles of the printing machine, the printing machine will normally be operated so as to perform but a single printing operation from each printing device which is passed through the machine.

The two clutches 117 and 120 are mounted on a main shaft 125 of the machine and the main shaft 125 is adapted to be driven by means of a constantly driven pulley 126 which is mounted thereon. The connection between the constantly driven pulley 126 and the main shaft 125 is provided by a one revolution clutch (not shown) 75

which is constructed and arranged so as to be engaged each time either one of the clutches 117 or 120 is to be driven through an operative cycle.

When the platen clutch 120 is engaged for operation through its one revolution cycle it serves to operate the platen mechanism P through a printing cycle, such actuation of the platen mechanism P being attained, through a train of drive mechanism which includes a vertically extending link 127. The link 127 is located so as to extend upwardly past the vertically extending portion 128 of a relatively rigid printing frame 129 which extends from a rear portion of the machine forwardly so as to overlie the printing position V and support the platen mechanism P for its operative movement. The platen mechanism P as herein shown comprises a carriage C which is mounted for reciprocation in a direction from front to rear of the machine upon a track which is provided on a plate 130 supported beneath the forward end of the printing frame arm 127. The platen mechanism P as herein shown is of the geared roller type and has a platen roller PR supported beneath the carriage C by means such as toggles 131 whereby the platen roller PR may be shifted from an elevated inactive position shown in Fig. 1 of the drawings to a lower or active position wherein the platen roller may be rolled along the upper face of a sheet to press the same into printing cooperation with a printing device D located at printing position V. The link 127 serves to impart reciprocatory movement to the carriage C through the medium of an arm 133 to which the upper end of the link 127 is connected. The arm 133 is fixed on one end of the shaft 134 which is mounted in a horizontal position in the printing frame arm 129. The shaft 134 extends to a point wherein it is located rearwardly of the carriage C, and a radial arm 135 fixed on this end of the shaft 134 is connected by means of links 136 to the carriage C so that when the shaft 134 is actuated through a rocking movement, the carriage C is moved through a reciprocating stroke.

45 The platen roller PR is located in its upper or inactive position when the carriage C is at the rearward limit of its movement, and in the course of a forward movement of the carriage C, the toggles 131 are actuated so as to shift the platen roller PR downwardly toward its lower or active position. This result is accomplished through the medium of means including a link 138 which is connected between the toggles 131 and the arm 135. Thus the first half of the operating cycle of 50 the platen mechanism may be termed the idle or conditioning portion of the cycle since during this period the platen roller is shifted downwardly or conditioned for its operative printing movement. After the platen roller PR has reached its lower or active position, it is maintained in this position during the return or rearward stroke of the carriage C so that the platen roller is rolled along the upper face of the sheet to produce the desired printing impression. After the 55 printing impression has been completed the link 138 is actuated to cause upward withdrawing movement of the platen roller. The platen roller PR is rotated as an incident to the reciprocating movement of the carriage C and this result is accomplished through means including the gears 139 shown in Fig. 1 of the drawings.

60 When the feed clutch 117 is engaged, it serves to actuate the feeding means which is associated with the printing device guideway of the machine, thereby to advance the printing devices from sta-

tion to station along said printing device guideway. In the machine illustrated in Figs. 1 to 6 the printing device guideway is relatively lengthy and includes angularly related paths of movement or guideways for the printing devices, but as it relates to the present invention, this form and arrangement of the printing device guideway is immaterial. It will be observed, however, that the printing device guideway of the machine shown in Figs. 1 to 6 includes advancing means such as carrier bars 140 illustrated in Fig. 4 of the drawings, such carrier bars 140 being reciprocable to impart the desired advancing movement to the printing devices. The portion of the printing device guideway which is shown in Fig. 4 of the drawings is that portion which extends beneath the magazine M, and in the course of a reciprocating movement of the carrier bars 140, the lower printing device D in the magazine M is withdrawn from the magazine and advanced to a station along the guideway which is indicated in Fig. 4 as station II and which constitutes a sensing station whereat detecting or sensing means S are operable to sense the presence or absence of identifying means such as the tabs 105 at selected identifying positions on the printing devices. The actuation of the various carrier bars 140 during the operative cycle of the feed clutch 117 is attained by means including a rockshaft 142 which, as shown in Fig. 4 of the drawings, has a generally radial arm 143 fixed thereon. The remote end of the arm 143 is connected by means of a link 144 to the carrier bars 140 so that in a rocking movement of the shaft 142 the desired reciprocating movement is imparted to the carrier bars 140. Thus in each actuation of the carrier bars 140 through a reciprocating stroke the printing devices D are advanced one station along the printing device guideway and in the machine shown in Figs. 1 to 6 the arrangement is such that several intermediate stations are provided along the printing device guideway between the sensing station II and the printing position V.

The machine shown in Figs. 1 to 6 is provided with an automatic selector mechanism 150, Fig. 3, which operates under the control of the sensing means S to produce print or skip operation of the printing machine with respect to each printing device as such printing device reaches printing position. The sensing means S operates to sense the presence or absence of identifying means as tabs at selected identifying positions on the printing device at the sensing station II, and the sensed indication is in this machine stored in a storage means incorporated in the selector mechanism 150 so that such sensed and stored indication is rendered effective to control the printing means or platen mechanism of the machine when the particular printing device from which the sensed indication has been derived reaches printing position. A wide variety of selector mechanism and sensing means might, of course, be employed in accordance with the present invention, but in the machine illustrated in Figs. 1 to 6 I have herein shown the selecting mechanism which is described in detail in the copending application of Carl J. Hueber, Serial No. 392,151, filed May 6, 1941, and reference may be had to said copending application for details of construction and operation thereof. It will be observed, however, in Fig. 5 of the drawings that the sensing means S includes a sensing head 151 which is mounted by means of guide rods 152 and 153 for vertical reciprocation along a path which is so located with respect to

the printing device guideway that sensing pins 154 carried on the sensing head 151 may in such reciprocation of the sensing head 151 be brought into sensing cooperation with respect to the identifying means carried on the printing device located at sensing station. The sensing head 151 is moved positively in an upward or retracting direction to the position shown in Fig. 5 of the drawings, and at the proper point in the cycle of operation of the machine the sensing head is allowed to move downwardly under the influence of yielding means not herein shown, and in the event that identifying means such as a tab 105 is located in such a position as to fall in the path of one of the sensing pins 154, the yieldingly induced downward movement of the sensing member 151 is terminated at a somewhat higher level than would be the case if a tab 105 were not encountered by a sensing pin 154.

The arrangement of the machine shown in Figs. 1 to 6 is such that the feed bars 140 which are associated with the guideway portion which underlies the magazine M come to rest at the end of a machine cycle in their rearward positions, that is their right-hand positions as shown in Fig. 4 of the drawings, and in the first half of the machine cycle, at the time when the platen mechanism P is being operated through its forward or conditioning stroke, the lower printing device in the magazine M is advanced to sensing station. At this same time, in the machine shown in Figs. 1 to 6, the printing device which has been previously located at the printing position V is discharged into the collector K and a new or different printing device is advanced along the printing device guideway into printing position. During this time the sensing head 151 is maintained in its elevated or inactive position, and at about the time when a new printing device has come to rest at the sensing station, the sensing head is allowed to move downwardly with a yielding action to sense the identifying means carried on this particular printing device. As the sensing head 151 moves downwardly a control cam 155, Figs. 3 and 5, is moved downwardly through a corresponding distance so that the control cam comes to rest at different positions in accordance with the sensed presence or absence of identifying means at the selected identifying positions on the printing device.

The control cam 155 is arranged to govern the yieldingly induced counterclockwise movement of a set-up arm 156, Fig. 3, which is arranged to set up a storage means in accordance with the operation of the sensing head 151. This storage means, as shown in Fig. 3, comprises a storage drum 157 capable of indexing movement on a horizontal axis provided by a shaft 158, and the storage drum 157 has a plurality of storage plungers 160 mounted thereon at angularly spaced points thereabout for longitudinal shifting movement parallel to the axis of the drum 157. The storage drum 157 is actuated through an indexing movement each time the printing device feeding mechanism is operated through a cycle, and this end is attained through a pawl and ratchet mechanism, Figs. 3 and 5, wherein the pawl 161 is carried on the arm 143 and is arranged to operatively engage a ratchet wheel 162 fixed on the shaft 158.

The set up action is applied to the storage plungers 160 in succession as these plungers reach a predetermined index or set up position, and the set up relationship of these plungers is utilized successively to effect a controlling action upon the printing mechanism of the printing ma-

chine as these plungers successively reach a control station. As the indexing movement of the drum 157 shifts the storage plungers 160 toward the lower or set-up position of the drum, a cam 163 acts upon pins 164 on the plungers 160 to withdraw the plungers to normal left hand positions (Fig. 3) from which they are subsequently shifted by the set-up arm 156. Such shifting or setting up of the plungers 160 takes place at the lower or set-up position of the drum 157. The number of cycles which elapses between the set up of a particular storage plunger 160 and the time when it exerts its controlling influence upon the printing mechanism of the machine is, of course, dependent upon the number of stations which are interposed along the printing device guideway between the sensing station II and the printing station V and is dependent also to some extent upon the nature of the controlling means which governs the engagement and disengagement of the platen clutch means. In the present instance a storage plunger 160, after having been set up in a particular cycle of the machine is advanced through two succeeding stations about the axis of the storage drum 160 without having any effect upon the printing means of the machine. In the next or third cycle which follows the setting up of a particular storage plunger 160, the storage plunger in the present machine may be operable upon control means to govern the operation of the printing means of the machine, but in the present machine the storage plunger 160 is even at this time effective only to produce a conditioning control operation which becomes effective upon the machine in the next or fourth cycle of operation. The details of the mode of construction and operation of this selecting means are fully described in the aforesaid copending application of Carl J. Hueber.

It will be evident, therefore, that the machine herein shown in Figs. 1 to 6 will in accordance with the controlling action of the selector mechanism 150 serve to cause print or skip operation of the printing machine under the control of the identifying means sensed upon the successive printing devices D, and in accordance with the present invention the printing machine is constructed and arranged so that when a printing device is to be passed through the machine without the performance of a printing operation therefrom, those parts of the machine which are to be operated in the particular cycle of the machine will be operated at a materially increased speed, thereby to increase the production capacity of the machine as a whole. Such automatic control of the operating speed of the machine is attained through means which is associated with and controlled by the sensing means S. In the present instance such control of the speed of the machine is attained by the provision of a storage means 170 which is generally similar in form to the storage means 150 and is indexed and set up concurrently with the corresponding operations performed upon the storage means 150. Thus the guide rod 153 of the sensing head 151 has a control cam 175, Figs. 3, 4, 5 and 6, carried on its lower end, and this cam 175 has a cam surface 176, Fig. 5, for controlling the operation of a set-up lever 177. The set-up lever is pivoted at 178 and has a cam roller 179 thereon adapted to bear against the cam surface 176. The cam roller 179 is held in engagement with the cam surface 176 by a spring 180 and when the sensing head 154 moves downwardly the set-up lever 177 is allowed to move in a counterclockwise direction,

Fig. 3, about its pivot 178 in an amount which is dependent upon the extent of downward movement of the sensing head 151. In such set-up movement of the set-up lever 177 this lever is operative to impart endwise movement to one of a plurality of control plungers 181, Figs. 3, 4 and 6, which are mounted about the periphery of a storage drum 182 at angularly spaced points. The storage drum 182 is fixed on the shaft 158 so as to be indexed by the pawl and ratchet mechanism 161 and 162. The shaft 158 as herein shown is carried in a pair of mounting plates 183 and 184 which are provided in the frame of the machine. As viewed in Fig. 3 of the drawings, the set-up movement of the storage plungers 181 is in a right-hand direction, and this set-up movement takes place while the plunger is located at the lowermost position or set-up position of the storage drum 182 indicated as position II in Fig. 4 of the drawings. The storage plungers 181 are set in normal left hand positions, Fig. 3, by means of a cam 185 which is engaged by pins 186 on the plungers 181 as they approach the lower or set-up position II of the storage drum 182. After a particular plunger has been set up the successive indexing movements of the storage drum 182 in a clockwise direction, Fig. 4, serve to move this set up storage or control plunger 181 through the requisite number of inactive intermediate positions, as positions III and IV indicated in Fig. 4, and this particular plunger is then moved to an upper or control position, indicated as position IV-T, wherein the set-up control plunger exerts its controlling action in a manner which will hereinafter be described in detail.

The control of the speed of operation of the mechanisms of the printing machine is in the present instance attained through the provision of two different sources of power operating at different speeds and which are selectively rendered effective under the governing control of the sensing means S, and in those instances where a relatively large number of stations are provided along the printing device guideway between sensing and printing stations, this controlling action is exerted through the medium of the storage mechanism 170. As herein shown the driving power for the machine is derived from a constantly driven motor 200, Figs. 1 and 2, having a pulley 201 on its drive shaft which is connected by a belt 202 to a pulley 203. The pulley 203 is fixed on a shaft 204 which is supported in suitable bearings between mounting places 205 and 206, the motor shaft and the shaft 204 being mounted parallel to the main shaft 125 of the machine. Thus the shaft 204 is driven at a constant speed, and two different driving speeds are derived from the shaft 204. One drive path, which may be termed the low speed drive for operating the machine when a printing operation is to be performed, includes a pulley 208, Figs. 1, 2 and 3, fixed on the shaft 204. The pulley 208 is connected by means of a belt 209 to a relatively large pulley 210 which is mounted for rotative movement on a clutch shaft 211. The clutch shaft 211 is mounted in the plates 205 and 206 parallel to the shaft 204. The other or high speed drive path is provided by a pulley 212 fixed on the shaft 204 and connected by means of a belt 213 to a pulley 214 which is rotatably mounted on the shaft 211. The pulley 214 is of a diameter which is considerably less than the diameter of the pulley 210 and hence the pulleys 210 and 214 are constantly driven from the shaft 204 in such a relationship

that the speed of the pulley 214 is considerably greater than the speed of the pulley 210. The relationship as herein shown is such as to drive the pulley 214 at a speed which is fifty per cent greater than the speed of the pulley 210.

The pulleys 210 and 214 are arranged for selective connection to the shaft 211 through a clutch device 215 which is positioned between the two pulleys 210 and 214, and the shaft 211 has a pair of pulleys 216 fixed thereon which are operable through belts 217 to transmit rotation of the shaft 211 to the main drive pulley 126 of the printing machine. The clutch means 215 as herein shown comprises a double faced cone clutch member 215' splined on the shaft 211 and movable in a left-hand direction as viewed in Fig. 3 into engagement with a complementary low speed element 218 fixed on the pulley 210 or in a right-hand direction, Fig. 3, into operative engagement with a high speed clutch member 219 which is fixed on the constantly driven pulley 214. The shiftable clutch member 215' may be shifted back and forth between these two engaged positions by means such as a clutch fork or lever 220 which depends from a pivot point 221 as shown in Fig. 2 of the drawings and has a pin and slot connection with the clutch member 215' for shifting the same back and forth along the shaft 211 between its two engaged positions. Since, as hereinafter will be pointed out, the shifting movement of the lever 220 and of the clutch member 215' is accomplished through one of the driven elements of the machine which derives its power through the clutch element 215', a relatively heavy fly wheel 222 is provided on one end of the shaft 211 to cause continued rotation of the shaft 211 during the periods of shifting movement of the clutch member 215'.

The clutch shifting lever 220 is arranged for actuation under control of the set positions of the storage plungers 181 of the storage mechanism 170, and to this end a link 225, Figs. 2, 3 and 4, has one of its ends connected to the lower end of the clutch shifting lever 220 so that the link 225 extends through the machine longitudinally thereof to a point relatively close to the storage mechanism 170 but located a considerable distance below and somewhat rearwardly of the storage mechanism 170 as will be seen in Figs. 3 and 4 of the drawings. The other or right-hand end of the link 225 as viewed in Fig. 3 of the drawings is connected to an arm 226 which is fixed upon the lower end of a vertically positioned rockshaft 227. The rockshaft 227 is mounted in a vertically extending sleeve 228 which is formed in the lower member 229 of a mounting bracket 230, this mounting bracket 230 being best shown in Fig. 4 of the drawings wherein it will be seen that the mounting bracket is suspended from front and rear mounting bars 231 and 232 which are provided in the machine parallel to the forward edge 101 thereof. At its upper end the rockshaft 227 has an arm 233, Figs. 3 and 4, fixed thereto so as to extend to the right as viewed in Fig. 3 of the drawings, and the requisite power may be applied to the arm 233 at the proper point in each machine cycle to impart the requisite shifting movements to the clutch member 215'. In the present instance such power is applied to the lever arm 233 by toggle means which includes toggle links 236 and 237, Figs. 3 and 4, pivoted together at their adjacent ends by a pivot pin 238. At its other end the link 236 is pivotally connected to the end of the lever arm 233 by a swivel block 239. The other end of the link

237 is mounted on a stationary pivot 240, Fig. 4, which is provided on the mounting bracket 230 at a point which is located somewhat rearwardly of the storage drum 182 and considerably below the storage drum. When the toggle means is in its extended position as shown in full lines in Fig. 4 of the drawings, it will be evident that the arm 233 will be actuated to its most counterclockwise position as shown in Fig. 3 of the drawings, and as a result the link 225 will be drawn to the right, Fig. 3, so as to engage the shiftable clutch member 215' with the high speed clutch member 219. When, on the other hand, the toggle means is shifted to its broken relationship shown in dotted outline in Fig. 4 of the drawings the swivel block 239 will, of course, be drawn to the left or forwardly from its position of Fig. 4, thereby to impart clockwise rotation to the rockshaft 227 and actuate the connecting rod 225 to the left in Fig. 3, thereby to shift the clutch member 215' into engagement with the low speed clutch member 218.

The power required for imparting such shifting movement to the toggle means and hence to the clutch member 215' is in the present instance derived from the arm 143 of the printing device feeding means, and such power is applied selectively to extend or to break the toggle means under the control of the set-up positions of the storage plungers of the storage mechanism 170. For this purpose the link 237 of the toggle means is formed as one arm of a bell crank, Fig. 4, and the other arm 245 of the bell crank extends upwardly to a point forwardly of the arm 143. At its upper end the arm 245 has a transverse pin 246, Figs. 3 and 4, mounted therein so as to project on opposite sides of the arm 245 parallel to the pivot pin 240. The pin 246 is adapted to be engaged by means which is driven by the arm 143 and this means in one manner of engagement with the pin 246 is operable to rock the arm 245 in a counterclockwise direction about its pivot 240 and in another manner of operation or engagement is operable to rock the arm 245 in a clockwise direction about its pivot 240. In the present instance this means comprises a pair of pawls 250 and 251 mounted on a pivot pin 252 provided on the arm 143 so that the clutch pawls 250 and 251 extend forwardly and overlie the oppositely projecting ends of the pin 246. It will be evident from a consideration of Fig. 4 of the drawings that the clutch pawl 250 has a forwardly facing shoulder 256 which may be engaged with the rear edge of the pin 246 to impart forward movement to the pin 246 and thereby rock the arm 245 in a counterclockwise direction, and it is through the action of the pawl 250 that the drive means is shifted to its high speed driving relationship. It will also be observed that the clutch pawl 251 has a rearwardly facing shoulder 257 formed thereon which may be engaged with the forward edge of the pin 246 to impart rearward movement to the pin with corresponding clockwise rocking movement of the lever 245, and it is through the action of the pawl 251 that the drive means is shifted to its low speed driving relationship.

The two clutch pawls 250 and 251 are selectively shifted between operative and inoperative positions with relation to the pin 246 by means under the control of the storage mechanism 170. To this end the storage plungers 181 of the storage mechanism 170 are arranged, in accordance with their endwise set positions to selectively actuate suitable linkage means which are opera-

tively connected to the clutch pawls 250 and 251. Thus when a storage plunger reaches the upper or control position on the storage drum 182, and the particular storage plunger is set in its right-hand position, as viewed in Fig. 3 of the drawings, a radially projecting cam lobe 181' on the storage plunger will engage a lever 260, Figs. 3 and 4, which is pivoted on an axis 261 provided on the mounting bracket 230. In Fig. 3 the plunger 181 which is located directly over the axis of the shaft 158 is shown in its right hand set up position wherein it is aligned with the lever 260, and the arrangement of the present machine is such that the plunger 181 is set up in this position when the operation of the sensing means indicates that the related printing device is to be skipped. A similar lever 262 mounted on the same axis is disposed to the left of the lever 260 as viewed in Fig. 3 of the drawings and when the operation of the sensing means indicates that a printing operation is to be performed from the sensed printing device, the related storage plunger 181 is set to what may be termed its left hand operative position, Fig. 3, wherein its cam lobe 181' is aligned with and will impart upward movement to the end of the lever 262.

The lever 260 imparts its controlling movement to the clutch pawl 250 through the medium of a link 264 which extends downwardly from substantially the midpoint of the lever 260 and is connected at its lower end to one end of a lever 265. A spring 266' acts on the lower end of the link 264 to urge the link downwardly and maintain the end of the associated lever 260 in engagement with the surface of the drum or with the surface of a cam lobe in the event that such cam lobe is aligned with the lever 260. The lever 265 is pivoted at 266 intermediate its ends on a pivot point provided on the mounting bracket 230, and at its other end the lever has a projecting pin 267 which extends into a vertical slot 268 formed in the lower end of a vertical link 270. The upper end of the link 270 is pivotally connected to the pawl 250. A generally similar link and lever connection is provided between the lever 262 and the pawl 251.

It will be evident that when the lever 260 is elevated to the position shown in Fig. 4 of the drawings through the action of a properly aligned cam lobe 181' on the upper storage plunger 181, the pin 267 will be moved downwardly, and hence the associated clutch pawl 250 will be allowed to move downwardly by gravity toward its operative engaging relation with respect to the pin 246. When, however, the lever 260 is allowed to pivot in a downward direction due to further indexing movement of the storage drum 182, the lever 265 is so rocked that the pin 267 is elevated and the clutch pawl 250 is shifted in an upward direction to disengage the same from the pin 246. This action is of a yielding character since it is attained through the operation of the associated spring 266'. A generally similar raising and lowering action takes place with respect to the pawl 251 when the lever 262 is operated by a properly aligned cam lobe 181'.

It will be recalled that when the toggle means 236-237 is in its broken position as is illustrated in dotted outline in Fig. 4 of the drawings, the clutch element 215' is engaged with the low speed clutch member 218. In the present instance this low speed driving connection constitutes the normal drive of the printing machine, and it is this low speed drive which is employed when a printing operation is to be performed. In some in-

stances, as in a case where but a small proportion of the printing devices are to be skipped, it may be found desirable to employ the normal or low speed drive even in the skip cycles of the machine, and means is therefore provided whereby the clutch means may be maintained constantly in its low speed driving relationship, thereby to disable the speed change means. This end is attained in the present instance through means including a link 280, Fig. 4, which has a slot 281 therein engaged with the central pivot pin 238 of the toggle means. When the link 280 is in the lower position shown in full lines in Fig. 4, the central pin 238 of the toggle means may be shifted back and forth within the slot 281 to thereby enable the desired clutch shifting and speed-change action to be attained, but when the link 280 is shifted in a downward direction as viewed in Fig. 4, the pin 238 is engaged by the upper end of the slot 281 and the toggle means is moved to and held in its broken relationship wherein the low speed drive is maintained constantly engaged. Such shifting of the link 280 is attained through a bell crank 282 pivoted at its midpoint at 283 and having a horizontal arm 284 connected to the upper end of the link 280. A downwardly projecting arm 285 of the bell crank 282 has an actuating link 286 connected thereto and this link extends forwardly through the machine to a control plunger (not shown) located on the front panel of the machine.

In some instances where the speed change mechanism is disabled as aforesaid, the operator may wish to continue to use the primary selecting mechanism 150 of the machine, and since the use of the selector mechanism 150 entails continued operation of the vertically shiftable sensing head 151, it will be obvious that the storage mechanism 170 will in such an instance be set up in each cycle of operation of the machine. The storage mechanism 170 will therefore tend to operate the two clutch pawls 250 and 251. The operation of the clutch pawl 251 will not be objectionable in such an instance, but since the clutch pawl 250 when shifted to its operative or lower position tends to shift the toggle means 236-237 to its extended relation, it is obvious that such operation of the clutch pawl 250 would be objectionable. For this reason means is associated with the disabling link 280 to shift the clutch pawl 250 to an upper or inactive position when the operation desires to disable the speed change mechanism. In the present instance this end is attained through the medium of a lever 290 pivoted at 291 on the lower portion 229 of the bracket 230. One end of the lever 290 underlies the lower end of the link 280, while the other end of the lever 290 is yieldingly connected through the spring 292 to the lower end of a vertically slideable plunger 270', and when the plunger 270' is raised its upper end engages the lower end of the link 270 associated with the pawl 250. It will be observed that the slot 281 in the link 280 has a substantial upward extension to provide for a substantial lost motion in a downward direction when the link 280 is to be rendered operative. As this lost motion is taken up, the clutch pawl 250 is shifted to its upper or inactive position, and the upper end of the slot 280 then engages the pin 238 to shift the toggle means 236-237 to its broken relationship. During such continued movement of the link 280 the spring 292 is tensioned and the pawl 250 is maintained at its upper or released position.

Operation of the machine shown in Figs. 1 to 6

Assuming for purposes of illustration that machine is at rest with the speed change mechanism in its high speed drive relationship and wherein the toggle means is in its extended relation of Fig. 4 and the clutch member 215' is engaged with the high speed clutch member 219 as shown in Fig. 3. In such an instance the machine is so conditioned that its next operative cycle will be a non-productive or skip cycle. Assuming further that the sensing means S has, in sensing the printing device which is related to the storage plunger 181 which is now located at position IV of the storage drum has determined that a printing operation is to be performed therefrom and has caused this storage plunger to be set up in a position wherein its cam lobe 181' is aligned with the lever 262, it will be evident that in the next indexing movement of the storage drum 182 this particular plunger 181 will be moved to position IV-T and will rock the lever 262 in an upward direction.

The arrangement of the present machine is such that the clockwise indexing movement of the storage drum 182 takes place in the first half-cycle of operation of the machine, during which time the arm 143 of the printing device advancing means rocks in a counterclockwise direction, Fig. 4, from its normal rearward position to the position shown in Fig. 4. Hence, when the lever 262 is rocked in an upward direction so as to rock the associated lever 265 and thereby lower the associated pin 267, the pawl 251 merely drops in a downward direction until a lower surface 251' thereof rests on the top of one end of the pin 246. Thus, the pawl 251 rides freely along the top of the pin 246 for a short distance until the lever 143 has substantially reached its forward position shown in Fig. 4. The pawl 251 then drops downwardly so as to locate the shoulder 257 thereof in an operative relationship with respect to the pin 246. As the motion of the arm 143 is reversed and the arm moves in a rearward direction, that is, a right-hand direction in Fig. 4, the shoulder 257 of the pawl 251 engages the pin 246 and rocks the lever 245 in a clockwise direction around its pivot 240. As a result the toggle means 236-237 is shifted to its broken relationship as shown in dotted outline in Fig. 4. It will be understood that the toggle means 236-237 is so constructed and arranged that it normally retains its extended relationship until a positive force is applied thereto in the manner described tending to move the toggle to its broken relationship. As an incident to the breaking of the toggle means 236-237, the lever 233 is rotated in a clockwise direction as viewed in Fig. 3 to thereby actuate the link 225 to the left, Fig. 3, and shift the clutch member 215' into engagement with the low speed clutch element 218, and it will be observed that this shifting action takes place during the last half of the machine cycle.

It will be understood, of course, that when the toggle means is to be shifted from one of its positions to the other there will be a period during which both of the pawls 250 and 251 will be located in their elevated positions so as to be in spaced relationship with respect to the pin 246. In other words, both of the pawls 250 and 251 will be in elevated positions such as that in which the pawl 251 is illustrated in Fig. 4. Hence, when the pawl 251 drops into its engaged or operative relationship with respect to the pin 246, the pawl 250 will be maintained in its elevated or inactive

position and the lever 245 and its pin 244 will be free of the pawl 250, thereby to enable the pawl 251 to accomplish the desired shifting of the lever 245 as above described. The shifting of the clutch means from its high speed to its low speed relationship as just described is accomplished by the pawl 251 in the last part of a machine cycle which is a skip cycle and at the end of such skip cycle the drive mechanism of the machine is conditioned for the performance of the next machine cycle at low speed, since the next cycle of the machine is to be a printing cycle. It should be observed, however, that since the fly wheel 222 in the first half of the cycle has been operating at this higher rate of speed, the last half of the skip cycle will be completed at high speed. In the first half of the next cycle, which is to be a printing cycle, the storage drum 182 is again indexed so as to release the elevated control lever 262 for downward movement by its spring 266'. Hence, the associated spring 266' acts through the associated lever 265 and link 270 to shift the pawl 251 to its elevated or inactive position. As the indexing movement of the storage drum 182 continues, the next storage plunger 181, which for illustrative purposes will be assumed to be set for a skip cycle of the machine, engages the lever 260 and elevates the same to substantially the position shown in Fig. 4. Thus the lever 265 which is associated therewith releases the pawl 250 for downward movement. Bearing in mind that at this time the lever 245 is displaced in a clockwise direction from the position shown in Fig. 4, it will be evident that a lower surface 250' on the lever 250 will engage the top of the pin 246 and the pawl 250 will remain in an upper or inactive position with respect to the pin 246 throughout the entire printing cycle of the machine in which it has thus been released for downward movement. This result follows for the reason that the forward rocking movement of the lever 143 has located the surface 250' over the pin 246 before the pawl 250 has been released. Hence, the machine continues at low speed through the printing cycle for which it has previously been set, and as the arm 143 reaches its rearward position at the end of this printing cycle, the surface 250' of the pawl 250 rides off of the pin 246 so as to locate the shoulder 256 in position for operative engagement with the pin 246 in the next machine cycle. Hence, after the next machine cycle has started, and in the first part of such cycle the shoulder 256 acts upon the pin 246 to shift the lever arm 245 in a counterclockwise direction toward the position shown in Fig. 4, and hence the toggle 236-237 is moved to its extended relationship early in the machine cycle to thereby shift the clutch member 215' into engagement with the high speed driving clutch member 219. As a result a high speed drive of the printing device feeding means is instituted during the first half of the machine cycle, and the fly wheel 222 is brought up to its higher speed. Hence, the skip cycle is completed at the higher speed as hereinbefore explained, even though the sequence in which the selector mechanism 170 has been set up may in some instances cause the mechanism to again shift to low speed drive during the last half of the machine cycle. In such an instance the next storage plunger on the storage drum 182 would be set for a printing operation, and the pawl 251 would be lowered to its effective position so as to cause return of the mechanism to the low speed drive during the last half of the cycle which has just been described. However, in the

event that the next storage plunger were set for another or second successive skip operation of the machine, the pawl 251 would, after a brief period of release wherein it might move downwardly to its active position, be returned to its upper or inactive position so that the toggle 236—237 would remain in its extended position. As a result the entire machine cycle in such a successive or second skip operation of the machine would take place at high speed in the first half as well as the second half of the machine cycle. Thus, it will be clear that in every skip cycle of the machine, a substantial portion of the cycle will be performed at a higher speed than is employed in the printing cycles, and where a plurality of skip operations of the machine follow in series, the high speed drive will be effective during the entire operating time of every skip cycle except the first, and hence the time required for feeding a given number of printing devices through the machine is materially reduced.

Alternative embodiment—Figs. 7, 8 and 9

As hereinbefore pointed out, the present invention is capable of utilization in printing machines of widely varying constructions, and the number of stations which intervene along the printing device guideway between the sensing station and the printing station is immaterial. Thus the invention is illustrated in Figs. 7 to 9 as embodied in a printing machine wherein the identifying means carried by the printing devices are sensed at the station which immediately precedes the printing station as contrasted with the embodiment shown in Figs. 1 to 6 wherein several stations intervene along the printing device guideway between the sensing station and the printing station.

The machine shown in Figs. 7 to 9 of the drawings is of the general character disclosed in the patent to Gollwitzer, No. 2,002,771, patented May 28, 1935, and in the patent to Hartley, No. 2,002,737, patented May 28, 1935, and as herein shown the machine provides a frame 300 having a table top T—1 across which sheets, forms and the like may be fed along a guideway G. The guideway G extends across a printing device guideway 302 along which printing devices D are fed in a step-by-step manner by a conveyor chain 303. The conveyor chain 303 has suitable lugs formed thereon for engagement with the rear edges of the printing devices, and the chain is supported by means including a sprocket 304. The printing device guideway intersects with the sheet guideway G thereby to provide a printing station, and the operation of the conveyor chain 303 is such that each printing device is brought to rest at the printing station thus provided. In this position the printing device is located beneath a platen P—2 which is of the stamper arm type and is carried on an arm 305 which is adapted to be rocked about a supporting pivot 306.

The platen P—2 is actuated in a printing stroke by a cam 307 carried on a sleeve 308 which surrounds a constantly rotating drive shaft 309. The drive shaft 309 may be operatively connected to the sleeve 308, and hence to the cam 307, by operation of a one-revolution clutch 310 and when the clutch 310 is engaged the platen P—2 is operated through a printing stroke each time the shaft 309 rotates through a complete revolution.

The clutch 310 includes a disc 311 fixed on the drive shaft 309 and carrying a clutch pawl 312 which is spring biased to the position shown in

Fig. 7 so as to tend to cause the nose 312' thereof to engage the adjacent edge surface of a lug 313 formed on the sleeve 308. Thus the clutch 310 tends to engage and to remain engaged, and a stop lever 314 is provided which may be shifted downwardly from the full line position of Fig. 7 to the dotted line position so as to be located in the path of rotation of the tail portion of the clutch pawl 312. Thus when the tail of the clutch pawl 312 strikes the stop lever 314, the nose 312' of the clutch pawl 312 is shifted out of engagement with the lug 313 thereby to allow the sleeve 308 and the cam 307 to stop in the positions which they occupy at the time when the clutch pawl 312 is disengaged. The stop lever 314 is biased toward its inactive or full line position by a spring 314' and is normally actuated and controlled by the mechanism which actuates the printing device advancing means, and this relationship will be described fully hereinafter.

The printing device advancing means, including the conveyor chain 303, is in the present instance operated through actuation of the sprocket 304, and to this end a feed rocker 315 is mounted on a shaft 316 beneath the upper run of the conveyor chain 303 and at one end of the rocker 315 a spring biased pawl 316 is mounted for operative engagement with a series of circumferentially spaced pins 317 provided on the sprocket 304. At the end of an advancing cycle of the printing device advancing means the rocker 315 occupies the position illustrated in Fig. 7 of the drawings, and in the course of operation or rotation of the main drive shaft 309, the feed rocker 315 is in normal cycles of operation of the machine operated through a conditioning cycle in a clockwise direction thereby to withdraw the pawl 316 from the pin 317 with which it is then engaged and cause the pawl to engage the next one of the pins 317. Such conditioning or clockwise movement of the feed rocker 315 takes place in what may be termed the first half of the cycle of operation of the machine, and during the last half of the cycle of operation of the machine the movement of the feed rocker 315 is reversed, or in other words the rocker moves in a counter-clockwise direction and the sprocket 304 is actuated so as to discharge the printing device from printing position and feed a new printing device to this position.

As described in detail in the aforesaid Gollwitzer and Hartley patents, such operation of the rocker 315 is obtained through a reciprocable plunger 318 constantly operated from the shaft 309 by an eccentric drive 318', and this plunger 318 is connected to the rocker 315 by a pawl 319 carried on an arm 315' of the rocker 315 and normally interlocked with the plunger by engagement with a collar 319' provided on the plunger.

During the first half of the machine cycle, or in other words during the time when the feed rocker 315 is moving through its conditioning stroke, a sensing head 320 which is operated in timed relation to the operation of the feed rocker 315 is moved yieldingly in a downward direction through a sensing stroke and suitable sensing means such as pins on the sensing head 320 are arranged to strike any tab or tabs 105 which may be mounted in corresponding identifying relation on the printing device D which is then at sensing station. In the event that a tab as 105 is encountered by the sensing means a rocker 321 which is associated with the sensing head operates to impart a predetermined downward movement to a

link 322, the upper end of the link 322 being connected to one arm 323 of a bell crank. The other arm 324 of the bell crank serves as a conditioning control means for selector mechanism which may govern the operative positioning of the stop lever 314. Thus the bell crank arm 324 has a head 325 having an outer surface which is concentric with the pivot point of the bell crank and a notch 326 is formed in this concentric surface. A control rocker 330 centrally pivoted as at 331 is arranged to be controlled by the positioning of the bell crank 323 and 324, and to this end a follower 332 is mounted on the control rocker 330 by means of a spring 334 so that the follower bears against the concentric outer surface of the head 325. When the follower 332 is seated in the notch 326, the control rocker 330 is located in the position shown in Fig. 7, while in the event that the bell crank 323—324 is rocked so as to engage the concentric surface thereof with the follower 332, the control rocker is actuated yieldingly in a counterclockwise direction. In such counterclockwise movement a tooth 335 on the rocker 330 is urged upwardly toward a position where it may engage an arm 336 which is operatively connected to the stop lever 314. When the arm 336 is thus engaged by the tooth 335 the stop lever 314 is held in its lower or active position thereby to maintain the clutch 310 disengaged. The stop lever 314 is normally actuated by means which is associated with the operating plunger 318, this means being such that at an intermediate point in the printing cycle of the platen P—2 the stop lever 314 is rocked from its full line position to its dotted line position in a positive manner. Since the machine shown in Fig. 7 is intended for continuous operation, the stop lever 314 is then released so as to be biased by its spring 314' toward its inactive or full line position and such retracting movement of the stop lever 314 takes place unless the tooth 335 has been engaged with the arm 336. While the manner of connection of the link 322 to the arm 323 may be varied as described in the aforesaid Gollwitzer and Hartley patents to effect reversal of the controlling action of the selector mechanism, such variation is immaterial in so far as the present invention is concerned, it being important only that the control rocker 330 be rendered operative to hold the stop lever 314 in its active position whenever a printing device D is to be skipped.

In accordance with the present invention the selector mechanism of the machine shown in Fig. 7 is utilized to increase the speed of operation of the machine in those cycles of operation where the printing device is to be skipped, and in attaining this end the controlling movements of the control rocker 330 are utilized to institute and govern appropriate operations of a speed change mechanism which may be similar to the speed change mechanism shown in the machine illustrated in Figs. 1 to 6. Thus the machine shown in Figs. 7 to 9 has a drive motor 350 connected by a belt 351 to an intermediate shaft 352. The intermediate shaft has a pair of pulleys 353 and 354 fixed thereon, and the pulley 353 acts through a belt 355 to drive a relatively large pulley 356 which is rotatably mounted on a clutch shaft 357. The other pulley 354 operates through a belt 358 to drive a somewhat smaller pulley 359 which is rotatably mounted on the clutch shaft 357 in spaced relation to the larger pulley 356. The clutch shaft 357 acts through a double belt connection 361 to drive a cross shaft 360 from which

drive is transmitted to the main shaft 309 of the machine.

The two pulleys 356 and 359 are thus driven at different speeds and are adapted to be selectively connected to the clutch shaft 357 through the medium of a clutch 365. The clutch 365 is of the double cone type having a shiftable clutch member 366 splined on the shaft 357 so as to be shiftable selectively into engaged relation with clutch members 367 and 368. The clutch member 367 is fixed on the pulley 356 so that when the clutch members 366 and 367 are engaged the shaft 309 of the printing machine will be driven at a low or normal speed which is adapted for the performance of the desired printing operations. The clutch member 368 is fixed on the pulley 358 so that when the clutch members 366 and 368 are engaged the shaft 309 of the printing machine will be driven at a somewhat higher speed, thereby to reduce the over-all time required for the completion of a machine cycle.

The clutch member 366 is adapted to be actuated by a clutch fork 370 carried on a shaft 371 mounted on a portion of the machine frame. The clutch fork 370 is located remotely with relation to the rocker 315, and the shaft 371 is therefore disposed so that its other end extends to a point substantially in the plane of the rocker 315, thus enabling the rocker 315 to be utilized to supply power for shifting of the clutch member 366. Thus an arm 375 is fixed on the other end of the shaft 371 in a position to be actuated from the rocker 315, and such actuation is controlled by the control rocker 330 of the selector mechanism.

The desired actuation of the arm 375 is attained by a pair of pawls 380 and 381 mounted on the lower end of a mounting arm 382 which is fixed on the rocker 315. The pawls 380 and 381 are arranged to extend to the left from the mounting arm 382, as viewed in Fig. 7, and their remote ends are positioned on opposite sides of the upper end of the arm 375. A pin 384 projects from opposite sides of the arm 375 and the ends of this pin are adapted to be engaged by suitable actuating shoulders on the pawls 380 and 381. When the clutch 365 is engaged in the manner shown in Fig. 7 the machine is conditioned to be driven at its low or normal speed, and when the location of the clutch member 366 is to be reversed for the purpose of causing operation of the machine at a high speed, the pawl 380 is lowered so that a shoulder 386 formed thereon may engage with the pin 384 during the conditioning stroke of the rocker 315 to thereby shift the clutch 365 to its high speed position. Since such shifting movement involves a period when the clutch member 366 will be disengaged from both of the driven clutch members, a fly wheel 387 is provided on the clutch shaft 359 to carry the driven parts of the machine through the intervening portions of the cycle. When the clutch member 366 is engaged with the high speed clutch member 368 the arm 375 is located in the dotted line position of Fig. 7, and when it is desired to return the clutch to its low speed position the pawl 381 is lowered so that a shoulder 389 thereon may engage the pin 384. The shoulder 389 faces in a direction opposite to the shoulder 386 and hence the shoulder 389 may operate to shift the arm 375 only in the active or counterclockwise movement of the feed rocker 315. The clutch 365 is maintained in either of its engaged positions by an over-center spring 375' acting on the arm 375.

The desired automatic control of the clutch

shifting pawls 380 and 381 is attained through a link 391 which extends downwardly from one end of the control rocker 330. The lower end of the link 391 is pivoted at 392 to an arm 393 fixed on one end of the shaft 394. The shaft 394 is mounted in frame portions 395 and carries a rocking beam 396 on its other end, the rocking beam 396 being located above and substantially in the plane of movement of the lever arm 375. One end of the rocking beam 396 has a link 397 connected thereto by a pin and slot joint 398, the slot of such connection being formed longitudinally in the link 397. The lower end of the link 397 is connected at 399 to the pawl 381. The other end of the rocking beam 396 is connected 15 to the upper end of a link 400 by a similar pin and slot connection 401 and the lower end of the link 400 is connected at 402 to the pawl 380.

The pawls 380 and 381 tend selectively, in accordance with the position of the rocking beam 396, to assume their lower or active positions, and since occasion will arise when automatic change of the operating speed will be unnecessary, means is provided for disabling the pawls 380 and 381. As herein shown this means comprises a bell crank 405 centrally pivoted at 406 and having a pin 407 projecting laterally from one arm thereof beneath the two pawls 380 and 381. An actuating rod 408 is connected to the other arm of the bell crank 405 so that the bell crank 405 may be rocked from its inactive position of Fig. 7 in a clockwise direction; thereby to elevate the pin 407 and raise the two pawls 380 and 381 to inactive positions.

Operation of the machine shown in Figs. 7 to 9

When the machine of Figs. 7 to 9 is at rest or at the end of a cycle with its elements in the relationship shown in Fig. 7, the speed change clutch 365 is engaged for low speed drive of the mechanism in the next cycle of operation. This indicates that when the printing device D, which is now at printing position, was at sensing station, the sensing thereof indicated that a printing operation was to be performed therefrom thereby setting the control rocker 330 and the rocking beam 396 in the positions shown.

As the machine enters upon the productive or print cycle for which it is set up in Fig. 7, the actuating rocker 315 of the printing device advancing means operates in the first half of the cycle to move in a clockwise direction through a conditioning stroke, and during this period the engagement of the clutch 310 drives the sleeve 308 and the cam means 307 and causes the platen P-2 to operate through an operative printing stroke. During this period the sensing head 320 operates through a sensing stroke and in the event that the printing device D at sensing station is intended to be skipped, the operation of the sensing head 320 will cause the rocking bell crank 323-324 to be rocked in an amount sufficient to move the notch 326 thereof out of engagement with the follower 332. Hence the spring 334 will be tensioned and the top surface of the rocker 330 will be engaged with the lower end of the arm 336. Hence, when the stop lever 314 is rocked downwardly from the full line position of Fig. 7 to its dotted line position, the arm 336 will ride along the top of the control rocker 330 until it is 70 aligned with the notch or recess in the control rocker, whereupon the spring 334 will shift the control rocker 330 additionally in a counterclockwise direction. After this action has taken place the force which has moved the stop lever 314 into 75

its active position is released, and the spring 314' acts to urge the stop lever toward its released position. This action, however, is limited to but a slight movement by interlocking of the tooth 335 with the arm 336, and hence the stop lever 314 is retained in its active position wherein it causes disengagement of the platen clutch 310 at the end of the cycle. Since the stop lever 314 is maintained in this active position until after initiation of the next machine cycle, the clutch 310 cannot engage in the next machine cycle, and hence the printing device which has been sensed to cause such disengagement of the clutch 310 is skipped when it reaches printing position.

After upward movement of the platen P-2 has started, the actuating rocker 315 reverses its movement and its pawl 316 engages the next pin 317 to thereby impart advancing movement to the conveyor chain 303, and in such movement the printing device D which has been sensed in the first portion of the cycle is shifted to printing position. At the same time the printing device from which a printing impression has just been made is discharged from printing position.

At the time when the control rocker 330 is shifted in a counterclockwise direction as aforesaid, the left hand end thereof, Fig. 7, is lowered from the position shown, thereby to actuate the rocking beam 396 in a clockwise direction. This 20 serves to elevate the pawl 381 and to release the pawl 380 for downward movement to its operative position. At the time when the pawl 380 is thus actuated the rocker 315 will have progressed through its conditioning movement to such an extent that the shoulder 386 will be located to the left of the pin 384, and a lower surface 380' of the pawl 380 will engage and slide along the pin 384. Thus the instant cycle of operation of the machine will continue and will be completed at low speed, and the pawl 380 may therefore be said to have been merely conditioned for operation. At the end of the cycle of operation the pawl surface 380' will ride off of the pin 384 and the shoulder 386 will be thereby positioned for engagement with the pin 384 at the beginning of the next cycle.

In the next cycle of operation, which is to be a skip cycle, the operation of the machine will start at low speed, since the clutch 365 is engaged with the low speed drive pulley, and through such low speed drive the rocker 315 will start upon its conditioning or clockwise stroke. In this conditioning stroke the pawl 380 operates to shift the clutch member 366 to its high speed position wherein it engages the clutch member 368 of the high speed pulley 359, the fly wheel 387 acting during an intermediate period to continue the low speed operation of the various driven elements. Immediately upon completion of such clutch shifting movement the driven parts are brought up to the desired high speed, thereby completing the skip cycle of the machine in less time than would be required if the low speed drive were employed throughout the cycle.

In the event that the printing device sensed by the sensing head 320 during such skip cycle is another printing device which is to be skipped, the pawl 381 is retained in its upper position and the high speed drive of the machine remains connected throughout the entire skip cycle in which the sensing takes place as well as during the initial portion of the next cycle.

When, during a skip cycle, the sensing means detects a printing device from which a printing

impression is to be made, the control rocker 330 is returned to the position shown in Fig. 7, whereupon the pawl 380 is elevated to its inactive position, and the pawl 381 is freed for downward movement at the time when the pawl 381 is thus released for downward movement, the conditioning movement of the rocker 315 has not been completed, and hence a surface 381' on the pawl 381 engages the pin 384 and rides along the pin until the conditioning movement of the rocker 315 is completed. The pawl 381 then drops to the position shown in Fig. 7 and the shoulder 389 thereof is conditioned for clutch shifting operation during the return stroke of the rocker. Since the skip cycle of the machine has started at high speed, the fly wheel 387 produces continued operation at this high speed until late in the cycle when the clutch shifting movement has been completed, the machine is then conditioned for operation in the next cycle at the desired low speed.

From the foregoing description it will be evident that the present invention enables skip operations in a printing machine to be performed more rapidly than print operations of the machine, thereby to pass printing devices which are to be skipped through the machine at a higher speed and effect a material saving of time. Moreover, this time saving operation of the machine is effected automatically in such a manner that economical and profitable machine operation may be attained even when but a small proportion of the printing devices in a group are to be utilized for making printing impressions.

Thus, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims.

I claim:

1. In a printing machine having advancing means for moving printing devices sequentially therethrough and operable in productive cycles with respect to selected of such printing devices and operable through non-productive cycles with respect to other of such printing devices, control means for causing selective operation of the machine through productive and non-productive cycles, a high speed drive having a clutch through which it may be rendered operative to drive said advancing means, a low speed drive having a clutch through which it may be rendered operative to drive said advancing means, clutch shifting means for said clutches operable to disengage the engaged one of said clutches and then to engage the other of said clutches, selectively operable actuating means for said clutch shifting means operated from the driven element of the engaged one of said clutches and governed by said control means, and inertia means associated with the driven elements of said clutches and operable to substantially maintain the operating speed of said driven members during clutch disengaging and engaging operations.

2. In a printing machine having advancing means for sequentially moving printing devices therethrough, driving means for operating said advancing means at either one of two speeds and including clutch means having a speed determining element shiftable in opposite directions to select the speed at which said advancing means is to be driven, said machine including a pair of pawls driven by said driving means first in one direction and then in the opposite direction in each machine cycle, means on one of said pawls operatively engageable with said element to shift said element in one direction, means on the other of said pawls operatively engageable with said element to shift said element in the other direction, and selector mechanism responsive to predetermined identifying means on such printing devices to operatively engage said pawls with said speed determining element selectively.

3. In a printing machine having a printing device guideway along which a plurality of stations are provided including sensing and printing stations, impression means at said printing station, advancing means for moving printing devices in a step-by-step manner along said guideway to the stations thereof, selector means responsive to identifying means on such printing devices, drive means for said impression means including an operating shaft and an impression clutch controlling operation of said impression means, a driving connection for said operating shaft, sources of low and high speed drive for said operating shaft, and means governed by said selector means and operated by said advancing means to selectively disconnect said impression clutch and drive said operating shaft from said high speed drive or to drive said operating shaft from said low speed drive when said impression clutch is connected.

4. In a printing machine having advancing means operable to move printing devices sequentially therethrough and into and then out of a plurality of positions including sensing and printing positions in the machine, impression means adapted to cooperate with a printing device at printing position to produce a printing impression therefrom and including an impression clutch and a control element therefor, sensing means adapted to sense identifying means carried by the printing devices as they are successively located at sensing position, means operable to drive said advancing means at a low speed or at a high speed, selectively, and including speed change clutch means, clutch control means driven by said advancing means for operating said speed change clutch means to render said drive means operable at low or high speed selectively, and means operable in the cycle in which each printing device is located at the station immediately preceding printing position to condition said control element of said impression clutch and said clutch control means of said speed change means for skipping the printing device when it reaches printing position and for operating said advancing means from said high speed driving means during such skip cycle of the machine.

ROBT. L. HATFIELD.
